EX

DESIGN FOR RIM-LOCK CASE.

Specification forming part of Design No. 11,240, dated June 10, 1879; application filed April 16, 1879.
[Term of patent 7 years.]

UNITED STATES PATENT OFFICE.

RODOLPHE CHRISTESEN, OF HARTFORD, ASSIGNOR TO THE RUSSELL & ERWIN MANUFACTURING COMPANY, OF NEW BRITAIN, CONN.

DESIGN FOR RIM-LOCK CASE.

Specification forming part of Design No. **11,240**, dated June 10, 1879; application filed April 16, 1879.
[Term of patent 7 years.]

To all whom it may concern:

Be it known that I, RODOLPHE CHRISTESEN, of Hartford, in the county of Hartford and State of Connecticut, have invented a new and useful Design for a Rim-Lock Case; and I do hereby declare that the following specification, taken in connection with the accompanying illustration, forming a part of the same, is a full, clear, and exact description thereof.

The novel design hereinafter described is adapted to the surface of a rim-lock case and striker-plate. It possesses the characteristic feature of being in the Japanese style of ornament.

Referring to the accompanying illustration, A represents the face of the lock-case, and B the ends of the same.

The face of the lock-case is ornamented as follows: Upon the lower side is arranged a geometrical border, a, and upon one end a border, b. The upper left-hand corner contains a section, c, of tile or fish-scale ornament, the lower left-hand corner a smaller section, d, of ornament of a similar character, and that portion of the surface on the extreme right is ornamented with a shrub bearing leaves and a geometrical flower. The central portion of

the face is occupied by an urn or vase, e, holding a flowering plant. On either side of this urn is located a figure. The one upon the right is standing upon a step, and is represented as receiving and saluting the figure upon the left. The former has a background of lattice-work, and a gate or portion of a fence is seen in the background of the latter. The scene is laid at the porch of a house, and is intended to represent the reception of a guest.

The ends of the lock-case are represented at B, where the general surface is shown as surrounded by a raised band, f, and dotted by slight projections. This surface is divided into two panels, g g', by compound geometrical ornament centrally located thereon, and each panel bears a portion of a flowering shrub and a butterfly or similar insect.

What I claim, and desire to secure by Letters Patent, is—

The Japanese design for a rim-lock case, substantially as described and shown.

RODOLPHE CHRISTESEN.
